UNITED STATES PATENT OFFICE.

WINFORD P. LARSON, OF MINNEAPOLIS, MINNESOTA.

PROCESS OF MAKING VACCINE AND PRODUCTS THEREOF.

Application filed March 27, 1918. Serial No. 225,027.

To all whom it may concern:

Be it known that I, WINFORD P. LARSON, a citizen of the United States, resident of Minneapolis, county of Hennepin, State of Minnesota, have invented certain new and useful Improvements in Processes of Making Vaccine and Products Thereof, of which the following is a specification.

The object of this invention is to provide a process or method of treating bacteria to obtain the antigenic principle thereof for use in the preparation of vaccines, or material to be used for purposes of immunization.

In the ordinary method of preparing vaccines from bacteria the antigens are produced in the form of particles. There are a few exceptions to this, such as diphtheria and tetanus toxins that are usually produced in a diffused state. Where the antigens are produced in the form of particles, these particles are seized upon by the phagocytes, in the blood, lymph or tissues, and digested, thereby interfering with immunization.

By means of the process herein described I am able to kill the bacteria and leave the bacterial mass in a state of diffusion.

In carrying out this process I prefer to subject the bacteria in suspension in a suitable fluid to a high pressure by means of a suitable gas and then to slowly release the fluid from the container in which it is held, and thereby, as the fluid passes out of its container, to permit a sudden expansion of the gas. This produces a sudden change in the osmotic tension of the fluid whereby the bacteria are killed, the expansion of the gas causing their disruption, and the juices, toxins and protoplasm of the organism are released in a diffused state and without any chemical change therein.

In the drawing which represents an embodiment of an apparatus that may be employed for carrying out my process, 2 represents the wall of a suitable gas tank containing gas, preferably carbon dioxide, under any desired pressure, 3 is a cap that is tapped into the wall 2, and 4 is an externally threaded tube fitting within said cap and made preferably of steel and hav-

ing a lining 5 of tin or similar material. 6 is a port which communicates with the tank and with the interior of the tube. 7 is a coiled spring seated on the cap 3 within the tube 4. 8 is an ordinary test tube fitting within the tube 4, seated on the spring 7, and having an open top, the walls of said test tube being spaced from the walls of the tube 4 to provide a circulating passage for the gas between them. 9 is a head having a recess 10 therein to receive the threaded end of the tube 4 and 11 is a socket in the bottom of said recess encircled by a flange 12. 13 is a concave seat in the bottom of said recess and 14 is a port leading from said seat into a chamber 15 provided in the upper part of the head 9. 16 is a seat encircling the port 14, and 17 is a valve carried by a cap 18 and fitting the seat 16 to close the port therein. The joint between the seat 17 and the valve is preferably sealed by means of a suitable gasket, 19. 20 is a gravity port leading from the chamber 15 to a spout 21 which may be connected to a test tube to which the bacteria are delivered.

A tube 13' has its upper end fitting within a socket 11 and its lower end resting on the bottom of the test tube 8 without forming a close joint therewith so that the fluid with the bacteria in suspension therein will be forced by the gas up through the tube 13' and into the chamber 15 when the valve 17 is opened.

In carrying out the process, water preferably distilled, or other fluid of low osmotic tension with bacteria in suspension is placed within the tube and connected with the gas under pressure. This gas is soluble in water and as it enters the test tube it dissolves in the fluid therein, and when the valve leading to the chamber is opened slightly, the fluid will be forced up through the port 14 and out into the chamber 15. As the fluid charged with gas leaves the port 14, the liberation or sudden release of the gas will destroy certain bacteria in the fluid or such bacteria may have been destroyed by the large amount of gas dissolved in the fluid. By this operation the bacterial cells will be disrupted and the protoplasm

or contents of the cells released. This material will be collected in the chamber 15 from which it may be drawn for use in making vaccines or immunizing material.

- 6 Vaccines are ordinarily prepared by growing the bacteria on a suitable culture medium, suspending them in salt solution and subjecting the same to heat sufficient to kill the bacteria. These dead organisms are 10 then injected into the individual at proper intervals in an effort to create immunity against the particular infection. The shortcomings of vaccines prepared by this method are (1) that the heat necessary to destroy 15 the bacteria changes them so that the dead bacteria do not form the immune bodies necessary to counteract the germs in the living state; (2) the dead germs injected are in a corpuscular or solid state and they are 20 taken up, that is, incorporated by the fighting cells of the body, commonly known as phagocytes, the result of which is that the vaccine is digested and hence its immunizing property is lost.
- 25 By my method of preparing vaccines it is not necessary to kill the germs by heat. They are killed by suspending them in a suitable fluid, usually distilled water, containing carbon dioxide under pressure. The 30 carbon dioxide dissolved in the water suspending the bacteria passes into the bacteria according to the law of osmosis. When the bacterial cells have been filled, so to speak, with this carbon dioxide, the pressure 35 is suddenly released, causing the gas to escape from the fluid and the bacteria, killing the latter by the sudden change in the osmotic tension of the fluid and at the same time disrupting them. The advantages of 40 preparing vaccines by this method are (1) the bacterial proteins are not denatured as is the case when heat is applied; (2) the germs are converted from the corpuscular or solid state to a colloidal or fluid state, 45 and as a result of this the bacteria cannot be surrounded and incorporated by the phagocytes and can, therefore, immunize the individual in a way that cannot be accomplished when the vaccines are employed, 50 made from bacteria killed by the usual methods.
- 55 While the apparatus herein illustrated and described is suitable for carrying out the process herein described and claimed, I do not limit myself to the use of any particular form or arrangement of the apparatus, as the steps constituting the process may be performed by means of any apparatus suitable for the purpose.
- 60 By a fluid of low osmotic tension as used herein I mean a fluid such as distilled water, which contains a minimum of solid matter in solution.

In my co-pending application Serial No.

223,781, filed March 21, 1918, Apparatus for making vaccine, I have described and claimed an apparatus or device suitable for carrying out the process herein described. It is obvious, however, that other devices differing from that illustrated in this application and described and claimed in my co-pending application may be used for performing the steps of this process.

I claim as my invention:

1. A process of making vaccine or immunizing material, consisting in subjecting the bacteria, held in suspension in a fluid having the quality of entering the bacterial cell by osmosis, to gas under pressure in such fluid, and then drawing off the mixture and liberating the gas, thereby killing and disrupting the bacteria and releasing the contents of the cells.

2. A process of treating bacteria for making vaccine or immunizing material, consisting in subjecting bacteria held in suspension in a fluid having the quality of entering the bacterial cell by osmosis within a closed chamber to a gas under pressure that is soluble in such fluid, then releasing the mixture and liberating the gas, thereby killing and disrupting the bacteria and releasing the contents of the cells.

3. A process of treating bacteria for making vaccine or immunizing material, consisting in subjecting bacteria held in suspension in a fluid of low osmotic tension to a gas under pressure soluble in such fluid, and then liberating the gas and thereby killing and disrupting the bacteria and releasing the contents of the cells.

4. A process of making vaccine or immunizing material, which consists in subjecting bacteria held in suspension in water or other fluid of low osmotic tension to a gas under pressure soluble in such fluid, and then drawing off the mixture and liberating the gas, and thereby killing and disrupting the bacteria and releasing the contents of the cells.

5. The process of producing vaccine which consists in subjecting material to a gas which is inert with relation to the material being treated under pressure for a period of time sufficient to cause the organisms in the material to become saturated, and then suddenly releasing the pressure whereby the sudden expansion of the gas within the organisms will disrupt the same.

6. The process of producing vaccine or immunizing material, which consists in subjecting bacteria to an inert gas for a period of time sufficient to cause the bacteria to become saturated by said gas, and then suddenly releasing the pressure, whereby the expansion of the gas within the bacterial cells will disrupt the same.

7. The process of producing vaccine or

immunizing material from pathogenic organisms which consists in subjecting such organisms to an inert gas under pressure for a period of time sufficient to cause said organisms to become saturated by the gas, whereby the sudden expansion of the gas within the organisms will disrupt the same. 8. Immunizing material or vaccine, in a colloidal or fluid condition, consisting of bacteria disrupted by internal gas pressure. In witness whereof, I have hereunto set and then suddenly releasing the pressure, my hand this 15th day of March, 1918. WINFORD P. LARSON.
